Primary Examiner — Selina Sikder(74) *Attorney, Agent, or Firm* — Howard IP Law Group, PC(57) **CLAIM**

The ornamental design for a remote control, as shown and described.

DESCRIPTION

FIG. 1 is a top right front perspective view of an embodiment of a remote control showing my new design;
 FIG. 2 is a front view thereof;
 FIG. 3 is a rear view thereof;
 FIG. 4 is a top view thereof;
 FIG. 5 is a bottom view thereof;
 FIG. 6 is a right side view thereof;
 FIG. 7 is a left side view thereof;
 FIG. 8 is a top right front perspective view of another embodiment of a remote control showing my new design;
 FIG. 9 is a front view of the embodiment of FIG. 8;
 FIG. 10 is a rear view thereof;
 FIG. 11 is a top view thereof;
 FIG. 12 is a bottom view thereof;
 FIG. 13 is a right side view thereof; and,
 FIG. 14 is a left side view thereof.
 The ornamental design which is claimed is shown in solid lines in the drawings. The broken lines in the drawings form no part of the claimed design.

1 Claim, 14 Drawing Sheets(56)
